UNITED STATES PATENT OFFICE.

LOUIS P. KREUDER, OF CHICAGO, ILLINOIS, ASSIGNOR TO BELL TAVERN SYSTEM, OF CHICAGO, ILLINOIS, A CORPORATION OF ILLINOIS.

DESIGN FOR A SIGN.

Application filed March 7, 1928. Serial No. 25,730. Term of patent 14 years.

To all whom it may concern:

Be it known that I, LOUIS P. KREUDER, a citizen of the United States, residing at Chicago, in the county of Cook, State of Illinois, have invented a new, original, and ornamental Design for Signs, of which the following is a specification, reference being had to the accompanying drawing, forming part hereof.

In the drawing Fig. 1 is a plan view and Fig. 2 a side view of a sign showing my new design.

I claim:

The ornamental design for a sign, as shown.
LOUIS P. KREUDER.
